(57) **CLAIM**

The ornamental design for a footrest for the side of an accelerator pedal in a vehicle, as shown.

DESCRIPTION

FIG. 1 is a front, left side perspective view, showing my new design;

FIG. 2 is a top, left side perspective view thereof, shown in a condition of use;

FIG. 3 is a top, left side perspective view thereof, shown in a second condition of use;

FIG. 4 is a top, left side perspective view thereof, shown in a third condition of use;

FIG. 5 is a left side elevation view thereof, the right side elevation view being a mirror image thereof;

FIG. 6 is a top plan view thereof;

FIG. 7 is a bottom plan view thereof;

FIG. 8 is a back elevation view thereof; and,

FIG. 9 is a front elevation view thereof.

The broken lines in FIGS. 2-4 illustrate environmental structure which forms no part of the claimed design.
